UNITED STATES PATENT OFFICE

2,541,412

CYLINDER BLOCK RIDGE GRINDER

Edward F. Frost, Le Sueur, Minn.

Application October 25, 1948, Serial No. 56,288

2 Claims. (Cl. 51—245)

1

This invention relates to a device for dressing the inner surface of a cylinder and has for its primary object to efficiently and conveniently remove the ridge from the top of worn cylinder blocks and to form a bevel on the top of the cylinder after removing the ridge so that new rings may be easily inserted and subsequent ring breakage and ring knocks will be obviated.

Another important object of this invention is to provide a cylinder ridge grinder having adjustable means for holding the grinder in the desired, correctly aligned position in a cylinder.

Another object of this invention is to provide means whereby the grinding wheels may be adjusted laterally in the cylinder relative to the retaining means and the operating means.

And yet another important object of this invention is to provide means whereby the grinding wheel and appurtenant driving parts may be moved around in an orbit to carry out the grinding of the bore of a cylinder and to remove the ridge from the top of the block.

These and ancillary objects and other meritorious features are attained by this invention, a preferred embodiment of which is set forth in the following description and illustrated in the accompanying drawings, wherein:

Figure 1 is a front elevational view of this invention, showing the same in operation for removing the ridge from the top of the cylinder bore;

Figure 2 is a side elevational view of this invention;

Figure 3 is a top plan view of this invention;

Figure 4 is a cross sectional view taken on line 4—4 of Figure 2;

Figure 5 is a vertical sectional view, showing the upper portion of the instant invention in elevation;

Figure 6 is a cross sectional view taken on line 6—6 of Figure 5;

Figure 7 is an enlarged fragmentary view of a modified form of grinding wheel, and,

Figure 8 is a sectional view through the superimposed adjusting gears for securing the upper and lower pair of centering jaws in the cylinder to operatively position the grinding wheel there-in.

In carrying out this invention, generally designated by the character reference 10, there is provided a casting 12 upon which is mounted a conventional electric motor 14. A driving shaft 16 extends downwardly from the motor and a cooling fan 18 is fixed thereon by means of a securing collar 20. The driving shaft extends vertically through the casting or housing 12. A miter gear 22 is fixed on the depending end of

2

the shaft and a ball bearing assembly 24 is disposed on the shaft behind the gear.

A complementary miter gear 26 is disposed at right angles in meshing engagement with the gear 22 and is fixed on a transverse shaft 28. The shaft 28 is preferably square or hexagon in cross section complementary to the cross sectional shape of the opening in the gear 26 and the collar 30 therefor so that the shaft can be slid in and out of the gear for adjustment purposes, as will be later described. Of course, a conventional ball bearing assembly 32 is disposed on the shaft in engagement with the collar 30, as seen in Figure 5. A miter gear 34 is disposed on one end of the drive shaft 28 and a complementary miter gear 36 is disposed at a right angle in meshing engagement with the gear. The gear 36 is disposed on a chuck shaft 38 which is vertically and rotatably disposed in a casing 40, having a lateral flange 42 which is bolted as at 44 to the casing 46 for the drive shaft 28. Of course, ball bearing assemblies 48 and 50 are disposed at the upper and lower end of the chuck shaft, the shaft terminating upwardly in a knurled knob 52, complementary in use to the hand tightening chuck 54 within which is held a cylindrical grinding wheel 56. Thus, to remove the grinding wheel or to insert a grinding wheel in the chuck, the knurled knob 52 is held and the chuck is rotated to open or close the jaws of the same.

To adapt the grinding wheel 56 for use with various sized cylinder bores, means is provided for moving the same laterally with respect to the housing 12. In this respect, the drive shaft 38 is disposed transversely in the reduced lower end of the housing on which the casing 46 is slidably disposed. The casing includes parallel side members 58 and 60 which are slidably disposed in opposed channels or guideways on the reduced lower end of the housing. One of the ends of the bars is secured to a bar support and bushing 62.

Means is provided for moving the casing inwardly and outwardly with respect to the housing 12 and comprises a shaft 64 which is rotatably but securely attached at one end to the flanged end of the casing, the shank of the shaft being externally threaded and disposed through a transverse bore in the reduced portion of the housing 12. The opposite end of the shaft is rotatably mounted in a flange 66. Means is provided for actuating the shaft 64 laterally in the housing to move the housing 40 inwardly and outwardly relative to the housing 12 and preferably includes a worm gear 70 having a

threaded bore in which is received the threaded shaft 64. The worm gear acts as a feed nut for the feed screw 64. The worm 68 meshes with the worm gear and is secured at its opposite end to an operating rod 71, the operating rod terminating in a conventional universal joint connection 72 which is affixed to a shaft upon which the worm is mounted. The rod 71 is bracketed by means of a bracket 74 and a bracket 76 to the side of the housing 12. The rod terminates in a knurled wheel 78, to which manual rotation can be applied for rotating the rod 71 and imparting rotation to the worm 68 and correspondingly moving the shaft 64, lateral movement of the shaft producing a lateral movement of the bars 58 and 60 and correspondingly a movement of the casing 40 for the chuck shaft 38.

The housing 12 is rotatably disposed on a supporting member 80, the supporting member having means for engaging the bore of a cylinder or a like work piece. In this respect, the housing 12 and more particularly the reduced portion thereof terminates in a centrally apertured head 82. The supporting member or casting 80 is provided with an upraised tapered spindle 84, the same being rotatably disposed in the central aperture in the head 82. A set screw 86 is provided for selectively preventing and permitting rotation of the spindle 84 relative to the head 82. A hand wheel 88 is formed on the upper end of the housing 12 so that movement of the hand wheel moves the housing 12 about the spindle 84 and produces an orbit movement of the grinding stone 56, the same being rotated through the drive shaft 28 and the armature shaft 16 of the motor.

Means is provided for retaining the supporting member 80 within the bore 90 of a conventional cylinder 92 and comprises an upper set of retaining jaws or arms 94 and a lower set 96. A sectional shaft 98 is vertically disposed in the center of the supporting member 80 and has secured on its opposite end a pair of operating gears or gear plates 100 and 102. The operating gears upon being rotated rotate the shaft 98 and the plates 100 and 102 attached thereto. The plates are provided with spiral grooves engaging cooperating teeth on the jaws to move the centering jaws 94 and 96 inwardly and outwardly with respect to the casting or supporting member 80. In this respect, a pair of diagonally placed operating shafts 104 and 106 extend into the casting 80 and are provided with gear ends 108 and 110. The gear 108 is disposed in meshing engagement with a gear 112 secured to the upper section of the shaft 98, while the gear 110 is in meshing engagement with a gear 114 secured to the lower section of the shaft. Thus, rotation of the actuating shaft 104 will rotate the gear 112 and the upper section of the shaft 98 and accordingly the operating plate 102 will actuate the upper set 94 of centering jaws. In a similar manner, rotation of the operating rod 106 will rotate the gear 114 and the operating plate 100 to move the lower set of jaws inwardly and outwardly.

The operating rods 104 and 106 are formed at their upper ends with square heads 116 complementary to a socket wrench 118 for rotating the same.

Means is provided for conducting a supply of electrical energy to the electric motor from a suitable supply source and includes an electrical conductor 118 which is connected to commutator brushes 120 carried by a brush ring 122. Slip rings 124 and 126 are disposed in wiping contact with the brushes, so that as the casting 12 is

rotated on the supporting member 80 by the hand wheel 88, the slip rings 124 and 126 are rotated within the brushes of the brush ring, the same being stationary, so that the conductor 118 is prevented from being tangled.

Attention is now directed to Figure 7, wherein there is illustrated the means provided for beveling the top of the cylinder after removing the ridge, as shown in Figure 5. In this respect, a grinding stone 128 is provided, the same including a tapered or conical body section 130 and an annular reduced end 132 and an upper disk-like end 134. It can thus be seen that when the conical intermediate section or tapered section 130 engages the top of the cylinder, it, as it rotates, imparts a bevel to the same. Another form of grinding wheel is illustrated in Figure 8, wherein the same includes complementary superimposed tapered wheels 136 and 138.

Thus, it can be seen that there is provided a novel and improved grinder, which is adapted for removing the ridge from the top of worn cylinder blocks. However, it is to be understood that the same can be employed effectively and dependably in grinding various other work pieces and in various other operations, wherein another tool could be substituted for the grinding stones 58 and 128. Accordingly, it is to be understood that while only one embodiment of this invention has been disclosed, that other embodiments and changes in details of structure may be carried out, the same coming within the spirit of the invention and the scope of the appended claims.

Having described the invention, what is claimed as new is:

1. A grinding device comprising: a supporting member adapted to be inserted in the work piece, said supporting member having a sectional shaft journalled therein, gearing means mounted in said supporting member for rotating said shaft, a plurality of plates on said shaft and rotatable therewith, said plates being provided with spiral grooves, jaws mounted in said member having teeth cooperating with said plates and being laterally reciprocated thereby, said jaws being engageable with the walls of the work piece for support, a housing rotatably mounted on said supporting member, a tool rotatably carried by said housing and laterally movable thereof, and actuating means mounted on said housing for rotating said housing and tool for moving said tool in an orbit about said housing.

2. A grinding device comprising: a supporting member adapted to be inserted in the work piece, said supporting member having a sectional shaft journalled therein, gearing means mounted in said supporting member for rotating said shaft, a plurality of plates on said shaft and rotatable therewith, said plates being provided with spiral grooves, jaws mounted in said member having teeth cooperating with said plates and being laterally reciprocated thereby, said jaws being engageable with the walls of the work piece for support, a housing rotatably mounted on said supporting member, a tool rotatably carried by said housing and laterally movable thereof, and actuating means mounted on said housing for rotating said housing and tool for moving said tool in an orbit about said housing, rotating means mounted within said housing and for driving said tool and the grinding wheel thereon for grinding the work piece.

EDWARD F. FROST.
